SHOE UPPER STRETCHING MACHINE

Euclid I. La Chapelle, Brockton, Mass., assignor
to United Shoe Machinery Corporation, Pater-
son, N. J., a corporation of New Jersey

Application October 21, 1936, Serial No. 106,765

15 Claims. (Cl. 12—97)

This invention relates to machines for stretching shoe uppers before they are mounted on their lasts and is herein illustrated in its application to a machine for applying lengthwise tension to that portion of a shoe upper extending from the throat portion of the upper to its rear end.

It is a general practice in the manufacture of shoes to stretch the shoe upper over the last by means of a pulling-over machine which stretches the upper lengthwise from its heel end to its toe end and stretches the upper widthwise in the region of the tip line of the vamp. When uppers are cut scant the seams uniting the quarters and the vamp are severely strained by the operation of the pulling-over machine and particularly by the operation of the side grippers which apply the widthwise tension to the forepart of the upper after the upper has been tensioned lengthwise thereof.

It is an object of the present invention to provide a machine for performing part of the lengthwise tensioning operation now performed by the pulling-over machine in order that the upper, as it comes to the pulling-over machine, may be in such a condition that that portion of the upper stretching operation remaining to be performed by the pulling-over machine may be performed without danger of straining the seams uniting the quarters to the vamp even though the upper may have been cut somewhat scant.

With the above object in view, the invention in one aspect thereof consists in the provision, in a machine for stretching lengthwise a shoe upper having a vamp and quarters united to the vamp by seams, of a shoe upper holding member herein illustrated as a form which engages the inner side of the shoe upper, including the seams uniting the vamp and the quarters, in the region of the throat of the vamp, a coacting shoe upper holding member herein illustrated as a strap which engages the outer surface of the shoe upper, including said seams, in the region of the throat of the vamp, a shoe upper holding member herein illustrated as a rear part form which engages the interior of the heel portion of the upper, and actuating means for effecting relative movement of said shoe upper holding members for stretching the shoe upper lengthwise from the heel to the throat of the vamp.

It is a further object of the invention to provide means for preventing dislocation of the rear part of the upper on the rear part holding member during the upper-stretching operation and with this object in view the invention in another aspect thereof consists in the provision of a shoe upper holding member constructed and arranged to engage the outer surface of the rear part of the upper and grip it against the inner rear part engaging member, said inner and outer rear part engaging members being provided with means,

herein illustrated as a tongue and a groove arranged for interengagement, for preventing the dislocation of the upper and holding the back seam portion of the upper straight during the lengthwise stretching operation.

In order that the upper may retain the stretch which is imparted to it by the machine, it is desirable for the stretching mechanism to maintain its tension on the upper for a substantial interval and this is accomplished in the illustrated machine without reducing the output of the machine by providing a plurality of shoe upper stretching mechanisms on a carrier, means for imparting intermittent movement to the carrier, a spring for actuating the upper-stretching devices, and means operating on the spring for releasing the stretching tension upon the upper preparatory to the removal of an upper which has been operated upon and the introduction of an unstretched upper into the machine. The means operating on the spring also energizes the spring for the next upper-stretching operation. As herein illustrated, the carrier is a rotary member which is operated through a Geneva movement and each of the upper-stretching assemblies is provided with a toggle mechanism for energizing the spring which operates the upper-stretching devices. In the illustrated machine the Geneva movement not only advances the carrier but also actuates the toggle to energize the spring and to release the stretching tension upon the upper to permit the upper to be removed and another upper to be introduced into the machine.

These and other features of the invention will now be described with reference to the accompanying drawings illustrating a machine embodying the invention and will be pointed out in the appended claims.

As shown in the drawings,

Fig. 1 shows a front elevation of a machine embodying my invention;

Fig. 2 is a vertical section through the said machine taken on line 2—2 of Fig. 1;

Fig. 3 is a plan view of one of the plurality of shoe upper stretching mechanisms;

Fig. 4 is a sectional view through the shoe upper stretching mechanism shown in Fig. 3, taken on line 4—4 of Fig. 3;

Fig. 5 is a sectional view taken on line 5—5 of Fig. 4;

Fig. 6 is a sectional view taken on line 6—6 of Fig. 4, and

Fig. 7 is a detail sectional view of the shoe upper heel-holding means.

Referring to Fig. 1 of the drawings, the illustrated machine is provided with a base plate 1, upon which two upright frames 2 and 3 are secured by bolts 4. The said two upright frames support a fixed shaft 5 which is secured to the upright frames by pins 6. Mounted free to rotate

on the said shaft 5 is a wheel or carrier 7 which consists of a hub 8 and of six radially extended arms 9. The upper ends of the said arms are provided with flanges 10 (Fig. 2) which form a supporting base for carrying the shoe upper stretching mechanism 11. The shoe upper stretching mechanism on each arm consists of a base plate 12, which is secured to the flanges 10 of the arms 9 by bolts 13 (Fig. 1). The rear portion of the base plate 12 has secured to it gibs 14 (Fig. 2) which provide a guideway in which is mounted a slideable support 17. A heel clamping member 18, which is adapted to engage the inner side of the shoe upper a, is rigidly connected to the slide 17 by a projection 19 (Fig. 4) which fits into a hole in the forward end of the slide 17 and which is securely fastened thereto. A co-acting heel clamping member 22, which is constructed and arranged to engage the outer side of the shoe upper a, is mounted on the slide 17 in ways 23 provided therein for movement lengthwise of the upper to clamp the shoe upper against the clamping member 18. The clamping movement is accomplished through a manually operated screw 24. The heel clamping member 18 is provided with a recess or groove 25 which extends heightwise of the upper and receives the back seam portion of the shoe upper a. The co-acting clamping member 22 is provided with a rib or tongue 26 which presses the back seam portion of the shoe upper into the groove 25 in the member 18. The clamping members 18 and 22 hold the back seam in straightened condition and from sidewise movement on the heel clamping member 18 and they also compress and flatten down the back seam of the shoe upper. With a shoe upper provided with a back stay instead of with a back seam, the back seam clamping members should engage the center of the back stay and thus hold the shoe upper properly centered during the stretching operation by holding the heel end thereof from sidewise movement on the heel clamping member 18. The clamping member 22 is preferably lined with rubber pads 27 (Fig. 7) at each side of the rib 26 to prevent damage to the shoe upper and, as shown, the rib projects beyond the pads sufficiently to enable the rib to press the back seam or back stay of the shoe upper into the groove 25 in the clamping member 18.

For holding or gripping the upper in the region of the throat of the vamp the forward part of the base plate 12 is provided with shoe upper holding means comprising a form 28 and an outer clamping member 30 (Fig. 6). The form 28 engages the inner side of the forepart of the shoe upper, including the forward portions of the seams uniting the vamp and the quarters. The shoe upper engaging portions of the said clamping member are preferably covered with a rubber pad 29 to prevent damage to the lining of the shoe upper. The outer clamping member 30, which is preferably in the form of a U-shaped strap, is also lined with a rubber pad 31 and is arranged to hold the upper in natural condition, that is to the approximate shape of a last, and is of a shape complementary to the shape of the clamping member 28. A recess 31' is provided to avoid engagement of the eyelets in the upper.

The lower ends of the strap 30 extend downwardly below the base 12 and are secured to a crossbar 32, the said crossbar being arranged to slide on pins 33 which are located on the under side of the base plate 12. Springs 34 are interposed between the base plate 12 and the sliding bar 32,

normally holding the strap 30 in downward clamping position. The sliding bar 32 also carries at each side cam rolls 35 which are adapted to engage fixed cam plates 36 mounted on the two upright frames 2 and 3. When the cam rolls 35 engage said cams, the crossbar 32 is raised against the compressing action of the springs 34, thus raising the clamping strap 30 away from the form 28, as best shown in Fig. 6, and providing sufficient space for inserting and removing the shoe upper from the clamping members, this space being preferably limited to preclude any liability of the operator's hand being introduced under the said clamping member 30.

The stretching of the shoe upper is accomplished by the provision of a strong compression spring 37 (Fig. 4) located between the forward end of the slide 17 and the end of an adjusting screw 38 which is carried by an abutment 12' of the base plate 12. The said adjusting screw is provided with a locking screw 39 to hold the said compression spring 37 in any suitable adjusted condition consistent with the type of shoe upper being stretched. To hold the said compression spring in proper alignment with the slide 17, said slide is provided with a long guide-pin 40 which passes through the said compression spring and also through the said adjusting screw 38. In the stopped position of the machine, as shown in Fig. 4, the slide 17 is held at the limit of its movement toward the toe end of the upper against the action of the compression spring 37 to release the shoe upper from strain preparatory to its removal from the machine and preparatory to the insertion of an unstretched shoe upper into the machine. The slide 17 is held in this position by a toggle mechanism comprising a pair of links 42 (Figs. 4 and 5) pivoted to a lug 41 on the slide and pivoted at their rear ends to a pair of links 43 which, in turn, are pivoted to the base plate 12. The toggle links carry cam rolls 44 which, just prior to the machine coming to a stop, engage fixed cam plates 45 for straightening out the toggle, thereby to force the slide 17 forwardly against the action of the compression spring 37 to release the shoe upper from lengthwise strain. At this time and just before the cam plates 45 operate to force the slide 17 forwardly the cam rolls 35 of the clamping member 30 engage the cam 36 to open up the said shoe upper clamping member 30, as best shown in Fig. 4.

After an unstretched shoe upper has been inserted in the machine and the wheel 7 has started to rotate, the cam rolls 35 drop off the cam 36, allowing the compression springs 34 to force the clamping strap 30 downwardly upon the shoe upper and upon the seams in the region of the throat of the vamp and against the clamping member 28, thus very firmly holding the forward part of the shoe upper from rearward movement in the machine. While this is taking place, the cam rolls 44 are riding on surfaces 45' of the cam 45, which surfaces are arranged in an arcuate path common to the direction of movement of the rolls with the wheel 7. As soon as the clamping action has taken place at the forward part of the shoe upper the cam roll 44 rides off of the cam 45, thus permitting the toggle 42 to buckle under the influence of the compression spring 37 and the full force of the compression spring 37 to stretch the shoe upper and its seams lengthwise.

To rotate the wheel 7 step-by step and also to hold it with the stretching mechanism in a predetermined stopped position, I have provided a

Geneva movement comprising a toothed rotor 46 secured on the hub 8 and a disk 48 pinned to a driving shaft 49 and provided with a stud which engages the teeth of the rotor 46. The said shaft is driven by an ordinary friction clutch 50 (Fig. 2), the movable element 51 of which is movable in and out of engagement with a driving pulley 52 by the action of a treadle 53 which is connected thereto by a link 53' and a bell-crank lever 54.

In order to stretch the inner or great toe side of the vamp and the seams at that side more than the opposite side of the vamp preparatory to the lasting in of the shank part, I have provided a toe support 55 (Fig. 3), which is herein shown pivoted to the forward end of the base plate 12, and so arranged that the operator may swing the said toe support so as to set the inner side (great toe side) of the vamp with the tip seam farther forward in the clamping members than the opposite side of the vamp preparatory to the actuation of the machine and to the clamping action of the clamping members 28 and 30.

In the operation of the machine, each of the six stretching mechanisms having been provided with a shoe upper, the operator first removes the automatically released stretched shoe upper from the horizontally disposed stretching mechanism on top of the machine, as shown in Fig. 1, mounts the stretched shoe upper on a last in any known manner and substitutes an unstretched shoe upper therefor in the machine. The operator then steps on the treadle and advances the wheel 7 sixty degrees in a clockwise direction to bring the next shoe back to the loading station. Thus each shoe upper remains under stretch for a sufficient period of time to retain a substantial amount of the stretch imparted to it by the machine.

Having thus described my invention, what I claim as new and desire to secure by Letters Patent of the United States is:

1. A machine for stretching shoe uppers lengthwise having shoe upper holding means constructed and arranged to engage the vamp and the quarters of the shoe upper in the immediate vicinity of the throat of the vamp for holding the shoe upper and the said seams from rearward movement, shoe upper heel-holding means in the form of coacting clamping members adapted to engage the heel end of the shoe upper at the inner side and at the outer side thereof, one of the said coacting clamping members having a recess which receives the back seam portion of the shoe upper and the other clamping member having a rib constructed and arranged to hold the back seam in the said recess.

2. A machine for stretching shoe uppers lengthwise having the elements recited in claim 1, and a spring for actuating the said shoe upper heel-holding means to stretch the shoe upper lengthwise.

3. A machine for stretching lengthwise a shoe upper having a vamp and quarters united to the vamp by seams comprising a shoe upper holding member which engages the inner side of the shoe upper, including the seams uniting the vamp and the quarters, in the region of the throat of the vamp, a coacting shoe upper holding member which engages the outer side of the shoe upper, including said seams, in the region of the throat of the vamp, a shoe upper holding member which engages the inner side of the heel of the shoe upper, and actuating means for effect-

ing relative movement of the said shoe upper holding members for stretching the shoe upper lengthwise from the heel to the throat of the vamp.

4. A machine for stretching lengthwise a shoe upper having a back seam and a vamp and quarters united to the vamp by seams comprising the elements recited in claim 3, and a back seam holding means.

5. A machine for stretching lengthwise a shoe upper having a vamp and quarters united to the vamp by seams comprising a shoe upper holding member which engages the inner side of the shoe upper, including the seams uniting the vamp and the quarters, in the region of the throat of the vamp, a coacting shoe upper holding member which engages the outer side of the shoe upper, including said seams, in the region of the throat of the vamp, a shoe upper holding member which engages the inner side of the heel of the shoe upper, a shoe upper holding member which engages the outer side of the heel of the shoe upper, and actuating means for effecting relative movement of the said shoe upper holding members for stretching the shoe upper and its seams lengthwise from the heel to the throat of the vamp.

6. A machine for stretching lengthwise a shoe upper having a back seam comprising a shoe upper holding member which engages the inner side of the shoe upper, including the seams uniting the vamp and the quarters, in the region of the throat of the vamp, a coacting shoe upper holding member which engages the outer side of the shoe upper, including the seams uniting the vamp and the quarters, in the region of the throat of the vamp, a shoe upper holding member which engages the inner side of the heel of the shoe upper, a shoe upper holding member adapted to engage the outer side of the heel of the shoe upper, back seam holding means in the form of a projection on the last-mentioned shoe upper holding member, and actuating means for effecting relative movement of the said shoe upper holding members for stretching the shoe upper lengthwise from the heel to the throat of the vamp.

7. A machine for stretching lengthwise a shoe upper having a vamp and quarters united to the vamp by seams comprising a shoe upper holding member constructed and arranged to engage the inner side of the shoe upper, including the seams uniting the vamp and the quarters, in the region of the throat of the vamp and to engage the upper substantially from edge to edge, a coacting shoe upper holding member constructed and arranged to engage the outer side of the shoe upper, including the seams uniting the vamp and the quarters, in the region of the throat of the vamp and to engage the upper substantially from edge to edge, a shoe upper holding member constructed and arranged to engage the heel of the shoe upper, and actuating means for effecting relative movement of the said shoe upper holding members for stretching the shoe upper and its seams lengthwise from the heel to the throat of the vamp.

8. A machine for stretching lengthwise a shoe upper having a back seam, a vamp, and quarters united to the vamp by seams comprising a shoe upper holding member constructed and arranged to engage the inner side of the shoe upper, including the seams uniting the vamp and the quarters, in the region of the throat of the vamp, a coacting shoe upper holding member con-

- structed and arranged to engage the outer side of the shoe upper, including the seams uniting the vamp and the quarters, in the region of the throat of the vamp, a shoe upper holding member constructed and arranged to engage the back seam of the shoe upper at the inner side of the heel end of the shoe upper, a coacting shoe upper holding member constructed and arranged to engage the back seam of the shoe upper at the outer side of the heel end of the shoe upper for preventing dislocation of the shoe upper and holding the back seam straight during the lengthwise stretching action upon the shoe upper, and actuating means for effecting relative movement of the said shoe upper holding members for stretching the shoe upper lengthwise from the heel end to the throat of the vamp.
9. A machine for stretching a shoe upper lengthwise having, in combination, a rotary carrier, a plurality of shoe upper stretching mechanisms mounted on the carrier, each mechanism having shoe upper holding means constructed and arranged to engage the forepart of the shoe upper and shoe upper holding means constructed and arranged to engage the heel end of the shoe upper, a Geneva movement for imparting intermittent movement to the rotary carrier, a spring for effecting relative movement of the shoe upper holding means to stretch the shoe upper lengthwise, means operating on the spring for releasing the stretching tension upon the shoe upper preparatory to the introduction of an unstretched shoe upper into the machine, and a single actuating means for the rotary carrier and for the spring compressing means.
10. A machine for stretching a shoe upper lengthwise having, in combination, a rotary carrier, a plurality of shoe upper stretching mechanisms mounted on the rotary carrier, each mechanism having shoe upper holding means constructed and arranged to engage the forepart of the shoe upper and shoe upper holding means constructed and arranged to engage the heel end of the shoe upper, means for imparting intermittent movement to the rotary carrier, a toggle mechanism for effecting relative movement of the said shoe upper holding means lengthwise of the shoe, and a single actuating means for the rotary carrier and the toggle.
11. A machine for stretching a shoe upper lengthwise having, in combination, a carrier, a plurality of shoe upper stretching mechanisms on the carrier, each mechanism having shoe upper holding means constructed and arranged to engage the forepart of the shoe upper and shoe upper holding means constructed and arranged to engage the heel end of the shoe upper, means for moving the carrier to present each shoe upper stretching mechanism in shoe upper receiving position for introduction of a shoe upper, a spring for effecting relative movement of the shoe upper holding means to stretch the upper lengthwise, means operating on the spring for releasing the stretching tension upon the shoe upper preparatory to the introduction of an unstretched shoe upper and for energizing the spring, and a single actuating means for operating the carrier and energizing the spring.
12. A machine for stretching a shoe upper lengthwise having, in combination, a carrier, a shoe upper stretching mechanism on the carrier comprising a shoe upper holding means constructed and arranged to engage the forepart of
- the shoe upper and arranged for closing movement heightwise of the upper, shoe upper holding means constructed and arranged to engage the heel end of the shoe upper and arranged for closing movement lengthwise of the upper, and a single actuating means for the shoe upper holding means which operates on the forepart and for the shoe upper holding means which operates on the heel end of the upper.
13. A machine for stretching a shoe upper lengthwise having, in combination, a movable carrier, a plurality of shoe upper stretching mechanisms mounted on the movable carrier, each mechanism having a shoe upper holding means constructed and arranged to engage the inner side of the shoe upper in the region of the throat of the vamp, a coacting shoe upper holding means constructed and arranged to engage the outer side of the shoe upper in the region of the throat of the vamp, a shoe upper holding means constructed and arranged to engage the inner side of the heel of the shoe upper, said shoe upper holding means being operable for yielding holding the shoe upper under lengthwise strain, actuating means for the said shoe upper holding means for stretching the shoe upper lengthwise from the heel to the throat of the vamp, and means for moving the carrier to present each shoe upper stretching mechanism in shoe upper receiving position for introduction of a shoe upper.
14. A machine for stretching a shoe upper lengthwise comprising a movable carrier, a plurality of shoe upper stretching mechanisms mounted on the carrier, each mechanism having a shoe upper holding member constructed and arranged to engage the inner side of the forepart of the shoe upper in the region of the throat of the vamp, a coacting shoe upper holding member constructed and arranged to engage the outer side of the forepart of the shoe upper in the region of the throat of the vamp, one of the said shoe upper holding members being arranged for movement towards and from the other shoe upper holding member, a shoe upper holding member constructed and arranged to engage the inner side of the heel portion of the shoe upper, actuating means for effecting relative movement of the said shoe upper holding members for stretching the shoe upper lengthwise from the heel to the throat of the vamp, means for imparting intermittent movements to the carrier to present each shoe upper stretching mechanism in shoe upper receiving position for introduction of a shoe upper, and actuating means on the said carrier moving means for releasing said forepart holding members preparatory to the removal of the stretched shoe upper from the machine.
15. A machine for stretching a shoe upper lengthwise comprising a movable carrier, a plurality of shoe upper stretching mechanisms mounted on the carrier, each mechanism having shoe upper holding means constructed and arranged to engage the forepart of the shoe upper, shoe upper holding means constructed and arranged to engage the rear part of the shoe upper and actuating means for moving the latter shoe upper holding means relatively to the former for stretching the shoe upper lengthwise, and means for intermittently moving the carrier to present each shoe upper stretching mechanism in a shoe upper receiving position for introduction of a shoe upper.
